UNITED STATES PATENT OFFICE

WILLIAM J. DE WITT, OF AUBURN, NEW YORK, ASSIGNOR TO SHOE FORM CO., INC.,
OF AUBURN, NEW YORK, A CORPORATION OF NEW YORK

SHOE FORM

Application filed March 19, 1930. Serial No. 436,993.

This invention relates to improvement in a shoe form, more particularly in a form comprising a hollow walled member adapted to be inserted in the toe of the shoe the 5 walls of the member terminating in flanges and a crossbar carried by the flanges and by which the distance between the walls of the member may be controlled.

Forms of this general type in which a 10 crossbar is provided for controlling the distance between the walls are well known. The crossbars of such forms however are generally pivoted at one end to the flange of one wall of the form and have a sliding or 15 adjustable connection at the other end to the flange of the other wall and the distance between the walls is determined solely by such slidable or adjustable connection.

One object of the present invention is to 20 provide a form in which the crossbar in addition to its slidable or adjustable connection includes means independent of this connection by which the distance between the walls is determined; more particularly 25 a crossbar having at its free end a curved portion which engages at all times one wall of the member and also a tongue which is adapted to enter one of a longitudinally extending series of perforations provided in 30 the flange of that wall.

Another object of the present invention is to provide upon the form a sprag or prong which when the form is positioned in a shoe is swung into engagement with the insole of the 35 shoe to prevent any unwanted or inadvertent movement of the form from its proper position.

Two embodiments of this invention are disclosed in the accompanying drawings, in 40 which;

Fig. 1 is a top plan view of a toe form with parts broken away embodying one form of this invention;

Fig. 2 is a cross section taken along the 45 line 2—2 of Fig. 1;

Fig. 3 is a similar view of a toe form embodying another form of this invention;

Fig. 4 is a cross section taken along the 50 line 4—4 of Fig. 3; and

Fig. 5 is a cross section taken along the

line 5—5 of Fig. 1 illustrating the relation of the prong to the insole of the shoe.

In both embodiments the form comprises a hollow toe member 10, preferably though not necessarily of resilient material, the 55 walls of which terminate in flanges 11 and 12 and are connected by a crossbar 15 attached to the flanges. Since these features are common to both embodiments the same reference numerals will be used throughout 60 the drawings.

In the embodiment illustrated in Figs. 1 and 2 one end of the crossbar 15 is pivoted to the flange 11 by a rivet or button 20. The other or free end of the crossbar 15 is 65 bent to form a substantially annular loop 21, a spring or a coil 22, and upwardly projecting tongue 23, and a portion 24 from which the tongue extends.

In the flange 12 of the form are provided 70 a longitudinally extending series of suitably spaced perforations 25 with any one of which the end 23 of the crossbar is adapted to engage. The loop 21 rests on the upper face of the flange, the coil 22 is at the inner 75 edge of the flange and the portion 24 extends below the flange. It will be particularly noted that the loop 21 is of such conformation that it rests in the angle 26 formed at the joinder of the flange 12 with the side 80 wall of the form 10 and bears at all times against such side wall.

In the embodiment shown in Figs. 3 and 4 the crossbar 15 is pivotally connected at one end by a rivet or button 30 to the flange 85 11. The other or free end of the crossbar is bent to form a loop 31 which, instead of being annular, is substantially triangular. That end of the crossbar also forms a coil 32 and terminates in a tongue 33 formed at the 90 end of a portion 24. The tongue is adapted to project through any perforations 35 of a longitudinally extending series formed in the flange 12. The loop 31 rests on the upper surface of that flange and has a snug 95 engagement with the angle 36 formed at the joinder of the flange 12 with the body 10 of the form while the portion 34 extends below the flange 12.

From the above description of the con- 100

struction it will be apparent that in each embodiment as the crossbar is swung on its pivot from the full line position (Figs. 1 and 3) to the dotted line positions the loop 5 21 or 31 bearing against the wall of the member will tend to separate the walls and hold them in such separation. When the crossbars are swung from the dotted line 10 positions of Figs. 1 and 3 to the full line 10 of positions the walls of the form if of resilient material normally tend to contract and such tendency is limited by the loops 21 and 31. The tongues 23 and 33 merely act to position the crossbar and prevent its unwanted 15 pivotal movement but they do not under ordinary conditions have any separating or limiting function.

The form 10 is substantially securely located in the toe of the shoe by the contact 20 of the walls but under certain conditions it has been found that the form slips out of its proper position and in order to prevent such movement I have provided a prong 40 as shown in Figs. 1, 2 and 5. The prong 40 25 is pivotally secured to the body of the form, preferably though not necessarily to the flange 11 as here illustrated. One manner of so securing the prong consists of a rivet or button 41. The body of the prong may 30 be curved as shown in Fig. 5 and terminates in a downwardly extending tongue 42 having a pointed tip 43. When the form is inserted into the shoe the prong 40 may be 35 swung as shown in Fig. 3 onto the flange 11 so that the tip 43 will not impede its movement. After the form has been finally located the prong 40 will be swung on its pivot into one of the positions shown in Fig. 1 40 with its tip 43 in contact with the insole 44 of the shoe. In the full line position any 45 tendency of the form to shift will be resisted by the edge of the flange 11 while in the dotted line position the tendency will be resisted by the button 41. The tip 43 may be 50 so faced that it will not resist the forward movement of the form and in such case the prong need not be swung into the position shown in Fig. 2. When the form is to be removed the tip 43 may be raised out of 55 engagement with the insole 44 either manually or by inserting a tool between the flange 11 and the prong 40. The prong may then be swung on its pivot until the tip rests on the flange 11, and is thus held out of contact with the insole.

While two embodiments of the invention have been shown and described it will be understood that I am not limited thereto since other embodiments can be made without departing from the spirit and scope of the invention as set forth in the following claims.

I claim:

1. A shoe form comprising a hollow toe member, the walls of which terminate in flanges, and a crossbar extending between

the walls thereof, one end of the crossbar being pivotally secured to one flange of the member, and the free end extending above the upper face of the other flange and bearing at all times against the wall which terminates in such flange whereby as the crossbar is swung about its pivot in one direction the walls of the member are separated. 70

2. A shoe form comprising a hollow toe member, the walls of which terminate in flanges, and a crossbar extending between the walls thereof, one end of the crossbar being pivotally secured to one flange of the member, and the free end extending above the upper face of the other flange and bearing at all times against the wall which terminates in such flange whereby as the crossbar is swung about its pivot in one direction the walls of the member are separated, the free end carrying means which engage the flange of that wall and limit the pivotal movement of the crossbar. 75 80 85

3. A shoe form comprising a hollow toe member, the walls of which terminate in flanges, and a crossbar extending between the walls thereof, one end of the crossbar being pivotally secured to one flange of the member, and the free end extending above the upper face of the other flange and bearing at all times against the wall which terminates in such flange whereby as the crossbar is swung about its pivot in one direction the walls of the member are separated, the flange of that wall having a longitudinally extending series of perforations and the free end of the crossbar carrying a tongue which, when it engages one of the perforations, limits the pivotal movement of the crossbar. 90 95 100

4. A shoe form comprising a hollow toe member, the walls thereof being flanged, and a crossbar pivotally attached at one end to the flange of one wall, the flange of the other wall having an arcuate longitudinally extending series of holes, the free end of the bar including a loop which rests upon the upper face of the perforated flange and bears at all times against the wall of the member which terminates in such flange whereby, upon the pivotal movement of the crossbar, the distance between the walls is determined and a tongue carried by the free end of the crossbar and adapted to engage one of the holes in the flange whereby the crossbar is held against such pivotal movement. 105 110 115

5. A shoe form comprising a hollow toe member, the walls thereof being flanged, and a crossbar pivotally attached at one end to the flange of one wall, the flange of the other wall having an arcuate longitudinally extending series of holes, the free end of the bar including a loop which rests upon the upper face of the perforated flange and bears at all times against the wall of the member which terminates in such flange whereby, upon the pivotal movement of the crossbar, 120 125 130

the distance between the walls is determined, a portion which rests against the under face of the perforated flange and a tongue carried by the free end of the crossbar and adapted to engage one of the holes in the flange whereby the crossbar is held against such pivotal movement.

6. A shoe form comprising a hollow toe member of resilient material the walls of which tend to approach each other and terminate in flanges, and a crossbar extending between the walls of the member, one end of the crossbar being pivotally secured to one flange of the member, and the free end 10 of the crossbar entering the angle of joinder between the wall and the other flange and bearing at all times against the wall whereby the walls of the member are positively separated when the crossbar is swung 15 about its pivot in one direction and the tendency of the walls to approach is limited when the crossbar is swung in the other direction.

7. A shoe form comprising a hollow toe member of resilient material the walls of which tend to approach each other and terminate in flanges, and a crossbar extending between the walls of the member, one end of the crossbar being pivotally secured to 25 one flange of the member, and the free end of the crossbar entering the angle of joinder between the wall and the other flange and bearing at all times against the wall whereby the walls of the member are positively 30 separated when the crossbar is swung about its pivot in one direction and the tendency of the walls to approach is limited when the crossbar is swung in the other direction, the free end of the crossbar carrying means 35 40 which engage the flange of that wall and limit the pivotal movement of the crossbar.

8. A shoe form comprising a hollow toe member of resilient material the walls of which tend to approach each other and terminate 45 in flanges, and a crossbar extending between the walls of the member, one end of the crossbar being pivotally secured to one flange of the member, and the free end of the crossbar entering the angle of joinder 50 between the wall and the other flange and bearing at all times against the wall whereby the walls of the member are positively separated when the crossbar is swung about its pivot in one direction and the 55 tendency of the walls to approach is limited when the crossbar is swung in the other direction, the flange of that wall having a longitudinally extending series of perforations and the free end of the crossbar carrying a tongue which when it engages any one 60 of the perforations limits the pivotal movement of the crossbar.

9. In a shoe form comprising a hollow toe member the walls of which terminate in 65 flanges, and a prong pivotally secured there-

to and having a tip which, when the form is located in the toe of a shoe, engages the insole of the shoe and prevents the unwanted removal of the form from its proper position, said prong being movable to a position of rest upon a flange of the form so that the tip is out of engagement with the insole of the shoe.

10. In a shoe form comprising a hollow toe member the walls of which terminate in flanges, and a prong pivotally secured to one flange of the form, and having a tip which, when the form is located in the toe of a shoe, engages the insole of the shoe and prevents the unwanted removal of the form from its proper position, said prong being movable to a position of rest upon a flange of the form so that the tip is out of engagement with the insole of the shoe.

Signed by me at Auburn, New York, this 17th day of March, 1930.
